HAND GRIP TOOL FOR MAKING AND
APPLYING WIRE HOSE CLAMPS

Charles W. Ray, Paducah, Ky.

Application June 28, 1946, Serial No. 680,179

3 Claims. (Cl. 81—9.3)

1

This invention relates to wire clamp tools, and more particularly to a tool for fabricating and applying wire clamps for hose connections and the like.

A main object of the invention is to provide a novel and improved wire clamp tool of relatively simple construction which is easy to operate and which is very efficient in performance.

A further object of the invention is to provide an improved tool for fabricating and applying wire clamps to various types of hose connections and for binding together various objects, said tool including means for forming the wire clamp to its preliminary shape, coiling the clamp for engagement with the object to be secured, tightening the clamp to secured position, locking the clamp in its tightened condition, and depressing the free end portions thereof into flush relationship with the adjacent surfaces of the secured object.

Further objects and advantages of the invention will become apparent from the following description and claims, and from the accompanying drawings, wherein:

Figure 1 is a side elevational view of a clamping tool constructed in accordance with the present invention.

Figure 2 is a longitudinal cross-sectional view of the tool of Figure 1.

Figure 3 is a top plan view of the tool of Figure 1.

Figure 4 is a vertical cross-sectional detail view of the coil winding structure employed in the tool of Figure 1, taken on line 4—4 of Figure 8.

Figure 5 is a detail view of the end portion of the tool taken on line 5—5 of Figure 1.

Figure 6 is a cross-sectional detail view taken on line 6—6 of Figure 3.

Figure 7 is an enlarged detail view showing a 40 coil forming member employed with the coil winding drum of the tool of Figure 1.

Figure 8 is a side elevational detail view, partly in cross-section of the coil forming structure employed in the tool of Figure 1, Figure 8 being taken on line 8—8 of Figure 4.

Figure 9 is a transverse cross-sectional view taken on line 9—9 of Figure 1.

Referring to the drawings, 11 designates an elongated body member comprising parallel side walls 13, 13 extending from one end to the other end of the body member. Secured between the side walls 13 adjacent one end of the body member 11 is a filler block 14 of suitable rigid material such as plastic, wood, or the like.

2

Journalled in the intermediate portion of body member 11 is a transverse shaft 15, which extends through the walls 13, 13 and extends outwardly a substantial distance at one side of the body member. Keyed on shaft 15 between the walls 13, 13 is a gear 16. Pivotally mounted on said shaft outwardly adjacent the walls 13, 13 is a lever member 17 having a downwardly concave channel-shaped handle portion 18 which overlies the rear portion of body member 11 and is formed to fit thereover. A leaf spring 19 is secured at one end to the lever member 17 and bears on the top surface of block 14, thereby biasing lever member 17 to a raised position.

15 The pivotal mounting of lever 17 is obtained by a pair of side lugs 12, 12 carried by said lever which rotatively engage shaft 15. Said side lugs are each formed with a bottom cutting jaw element 20 adapted to cooperate with an opposing cutting jaw element 21 formed on the adjacent wall member 13, whereby wire cutting action may be obtained by rotating handle 18 downwardly toward body member 11 with the wire interposed between jaw elements 20 and 21.

20 25 Journalled in walls 13, 13 forwardly of shaft 15 is a second transverse shaft 22 on which is keyed a gear 23 which is in mesh with gear 16. Shaft 22 projects outwardly from the walls 13, 13 on each side of the body of the tool, the outwardly projecting ends of said shaft being each formed with a notch 24.

30 35 Pivottally secured to lever 17 is a pawl 25 which is biased into ratchet engagement with the gear teeth of gear 16 by a leaf spring 26 secured to the end of block member 14. When lever 17 is moved downwardly, pawl 25 rotates gear 16 and thereby causes gear 23 and shaft 24 to be rotated counterclockwise, as viewed in Figure 2.

30 Secured between the forward end portions of walls 13, 13 is a nose member 26 formed with a transverse V-notch 27 at its forward end. Secured to the rearward portion of nose member 26 is a rearwardly extending leaf spring member 29 which engages gear 23 with ratchet cooperation therewith, allowing said gear 23 to be rotated counterclockwise but preventing clockwise rotation thereof.

35 40 Rotatively journalled in nose member 26 is a transverse pin 30. Welded to the externally projecting ends of pin 30 are a pair of lugs 31, 31 carried by a channel-shaped lever member 32 which is adapted to underlie and receive the bottom edges of walls 13, 13. Provided on each side of nose member 26 above and below pin 30 are a 55 pair of shearing lugs 33, 33. Formed in pin 30

adjacent each pair of shearing lugs is a bore 34 adapted to receive a wire therethrough. When the wire is positioned in the bore it may be sheared off by rotating lever member 32 downwardly, thereby causing shearing cooperation to occur between bore 34 and a shearing lug 33.

Rotatably mounted on shaft 15 is a drum 35. Pivotally secured to the end of drum 35 at 36 is a handle 37. Handle 37 is formed with an aperture 38 encircling shaft 15. Said aperture is provided with a shoulder 39 and adjacent shoulder 39 said shaft is formed with a cooperating shouldered recess 40 shaped to engage with shoulder 39 when handle member 37 is rotated counterclockwise as viewed in Figure 8. In this direction of rotation of the handle 37 shaft 15 may be rotated thereby. In the opposite direction of rotation of handle 37 drum 35 is rotated independently of shaft 15.

Drum 35 is formed with a pair of recesses 41, 41 adapted to receive a pair of wire ends. Secured to the body of the tool in overlying relation to drum 35 is a guide arm 42 formed with a bottom recess 43 adapted to maintain a pair of wires in parallel positions as the wires are coiled on drum 35 during the process of forming a clamp coil.

Secured between the rear ends of walls 13, 13 is a tail member 44 formed with an end spur 45 and a pair of notched side spurs 46, 46.

In forming the clamp, a length of wire is cut off and is bent into U-shape. For this purpose the lower edges of lever member 37 are notched, as shown at 47, and the adjacent top surface of body member 11 is formed with a transverse groove 48. The mid portion of the length of wire is placed in groove 48 and handle 18 is depressed, causing notches 47 to engage the wire and bend said wire to the required U-shape. The free ends of the U-shaped wire are then inserted in recesses 41 of drum 35 and the handle 37 is rotated clockwise as viewed in Figure 8, causing the wire to be coiled on the drum to its desired clamping configuration. The coil wire is then removed from the drum and is engaged around the object to be clamped, the free ends of the coil being positioned under the transverse straight center portion thereof. Said free ends are then threaded through bores 34, 34 of the nose pin member 30 and are respectively inserted in the notches 24, 24 of shaft 22. With the U-shaped notch 27 of the nose member in engagement with the transverse straight center portion of the wire loop, handle 37 is rotated counterclockwise as viewed in Figure 8, causing the free ends of the wire to be coiled on the laterally projecting ends of shaft 22. When the clamp has been drawn approximately to the desired degree of tightness on the object engaged thereby additional tension is applied thereto by moving handle 18 downwardly several times until the final desired tightness of the clamp is obtained. The entire tool is then rotated forwardly over the fulcrum provided by the transverse straight center portion of the wire loop, thus bending the wire adjacent said straight portion into reversed position. Lever 32 is then rotated, whereby the superfluous wire is sheared off. The free ends of the wire clamp are then depressed into substantially flush position into the surface of the object by hooking spur 45 of the tail member 44 under the straight transverse portion of the clamp, engaging the respective wire ends in the notched side spurs 46, 46 and rotating the tool downwardly, thus embedding said wire ends in the surface of the object.

While a specific embodiment of a wire clamp tool has been disclosed in the foregoing description, it will be understood that various modifications within the spirit of the invention may occur to those skilled in the art. Therefore, it is intended that no limitations be placed on the invention other than as defined by the scope of the appended claims.

What I claim is:

1. A tool for fabricating and applying a wire clamp to a hose comprising an elongated body member, a shaft disposed transversely in said body member and carried by the latter, a drum rotatably mounted on said shaft adjacent an end thereof, said drum being provided with a pair of recesses arranged in spaced parallel relation and extending inwardly from the periphery thereof for the reception therein of the ends of a U-shaped wire, a handle having an aperture encircling said shaft and pivoted to the outer end of said drum operable upon rotation in a clockwise direction to thereby convert the U-shaped wire into a wire loop, a gear carried by said shaft, a second shaft disposed transversely in said body member and arranged in spaced relation with respect to said first-named shaft, a second gear carried by said second shaft and in meshing engagement with said first-named gear, a nose member on the end of said body member adjacent said second shaft for supporting the intermediate portion of the wire loop, a transverse pin on said nose member, said pin having a pair of transversely-extending bores arranged in spaced parallel relation for the passage of the ends of said wire loop therethrough, said second-named shaft having each of its ends projecting beyond said body member, each of the projecting ends of said second-named shaft being provided with a notch, the notches of said second shaft being in alignment with the bores in said pin and receiving the ends of said loop, and co-acting means on a wall of the aperture of said handle and on said first-named shaft operable upon rotation of said handle in a counter-clockwise direction for connecting said drum to said first-named shaft to thereby cause the coiling of the ends of the loop in the notches of said second-named shaft about the latter.

2. A tool for fabricating and applying a wire clamp to a hose comprising an elongated body member, a shaft disposed transversely in said body member and carried by the latter, a drum rotatably mounted on said shaft adjacent an end thereof, said drum being provided with a pair of recesses arranged in spaced parallel relation and extending inwardly from the periphery thereof for the reception therein of the ends of a U-shaped wire, a handle having an aperture encircling said shaft and pivoted to the outer end of said drum operable upon rotation in a clockwise direction to thereby convert the U-shaped wire into a wire loop, a gear carried by said shaft, a second shaft disposed transversely in said body member and arranged in spaced relation with respect to said first-named shaft, a second gear carried by said second shaft and in meshing engagement with said first-named gear, a nose member on the end of said body member adjacent said second shaft for supporting the intermediate portion of the wire loop, a transverse pin on said nose member, said pin having a pair of transversely-extending bores arranged in spaced parallel relation for the passage of the ends of said wire loop therethrough, said second-named shaft having each of its ends projecting beyond said body

member, each of the projecting ends of said second-named shaft being provided with a notch, the notches of said second-named shaft being in alignment with the bores in said pin and receiving the ends of said wire loop, co-acting means embodying a shoulder on a wall of the aperture of said handle and a shouldered recess on said first-named shaft operable upon rotation of said handle in a counter-clockwise direction for connecting said drum to said first-named shaft to thereby cause the coiling of the ends of the loop in the notches of said second-named shaft about the latter, a shearing lug on said nose member arranged in alignment with each of the bores in said transverse pin, and a lever member carried by said transverse pin operable upon rotation downwardly to shear the wire ends.

3. A tool for fabricating and applying a wire clamp to a hose comprising an elongated body member, a shaft disposed transversely in said body member and carried by the latter, a drum rotatably mounted on said shaft adjacent an end thereof, said drum being provided with a pair of recesses arranged in spaced parallel relation and extending inwardly from the periphery thereof for the reception therein of the ends of a U-shaped wire, a handle having an aperture encircling said shaft and pivoted to the outer end of said drum operable upon rotation in a clockwise direction to thereby convert the U-shaped wire into a wire loop, a gear carried by said shaft, a second shaft disposed transversely in said body member and arranged in spaced relation with respect to said first-named shaft, a second gear carried by said second shaft and in meshing engagement with said first-named gear, a nose member on the end of said body member adjacent said second shaft for supporting the intermediate portion of the wire loop, a transverse pin on said nose member, said pin having a pair of trans-

versely-extending bores arranged in spaced parallel relation for the passage of the ends of said wire loop therethrough, said second-named shaft having each of its ends projecting beyond said body member, each of the projecting ends of said second-named shaft being provided with a notch, the notches of said second-named shaft being in alignment with the bores in said pin and receiving the ends of said wire loop, co-acting means on a wall of the aperture of said handle and on said first-named shaft operable upon rotation of said handle in a counter-clockwise direction for connecting said drum to said first-named shaft to thereby cause the coiling of the ends of the loop in the notches of said second-named shaft about the latter, a lever pivotally mounted on said first-named shaft and operatively connected to said first gear operable upon downward movement to thereby tension the coiled ends of the loop, and resilient means operatively connected to said lever for biasing the latter to its normal position.
